(57) **CLAIM**

The ornamental design for a battery cover, as shown and described.

DESCRIPTION

FIG. 1 is a perspective view of the battery cover according to one aspect of the present invention.

FIG. 2 is a top view of the battery cover illustrated in FIG. 1. FIG. 3 is a bottom view of the battery cover illustrated in FIG. 1

FIG. 4 is a front view of the battery cover illustrated in FIG. 1. FIG. 5 is a rear view of the battery cover illustrated in FIG. 1. FIG. 6 is a first side view of the battery cover illustrated in FIG. 1; and,

FIG. 7 is a bottom view of the battery cover illustrated in FIG. 1.

The surface shading and broken lines shown in FIGS. 1-7 represent portions of the battery cover that form no part of the claimed design.
